ATTORNEY

UNITED STATES PATENT OFFICE

90,672

DESIGN FOR A MERCHANTISING CABINET

Calvin C. McGaugh, Dallas, Tex.

Application September 20, 1932
Serial No. 45,003

Term of patent 14 years

To all whom it may concern:

Be it known that I, CALVIN C. McGAUGH, a citizen of the United States, residing at Dallas, county of Dallas, State of Texas, have invented a new, original, and ornamental Design for Merchandising Cabinets, of which the following is a specification, reference being had to the accompanying drawing, forming a part thereof.

Fig. 1 is a perspective view of the cabinet of my new design.

Fig. 2 is a horizontal section taken on the line 2—2 of Fig. 1.

I claim:

The ornamental design for a merchandising cabinet, as shown.

CALVIN C. McGAUGH.
